BLAST NOZZLE

Walter G. Schwartzkopf, St. Louis, Mo.

Application July 9, 1931. Serial No. 549,608

2 Claims. (Cl. 51—11)

This invention relates to new and useful improvements in blast nozzles for use for feather edge work in stone. Sand blast nozzles for use on stone are well known in the art. However, these nozzles have been heretofore so constructed that they could not be used for fine or feather edge work, such as lettering or inscribing small designs. The discharge mouth or opening in these nozzles is more than one-eighth of an inch in diameter with the result that the abradant material is discharged therefrom in a stream which cannot be utilized in blasting letters or other fine designs on stone.

The primary objects of my invention are to provide a nozzle, the discharge mouth or opening of which is not more than 0.075 of an inch in diameter so that the abradant material is discharged therefrom in a stream which can be used in inscribing or blasting on stone letters or designs of fine proportions.

Other objects of the invention are to provide an improved nozzle which is highly efficient in operation and is so constructed that the wear thereon by the abradant material is reduced to minimum, thereby prolonging the life and usefulness of the nozzle.

Additional objects of the invention are to provide a nozzle holder which can be conveniently held by the operator in inscribing letters and fine designs on stone and wherein the parts most subjected to wear are formed detachable and can be replaced when worn.

With these and other objects in view, my invention consists in certain novel features of construction and arrangement of parts hereinafter more fully described and claimed, and illustrated in the accompanying drawing, in which—

Figure 1 is a side elevational view of my improved holder having attached thereto a flexible hose connection supplying compressed air and abradant material and provided with a discharge nozzle of my improved design.

Figure 2 is an enlarged longitudinal cross section through the holder and the nozzle.

Figure 3 is an enlarged longitudinal cross section through the nozzle.

Figure 4 is an end view of the latter.

Referring by numerals to the accompanying drawing, 10 indicates a holder provided with a longitudinal bore 11 and having one end formed with a threaded extension 12 for receiving a detachable connector 14, while the other or forward end of the holder has the end of its bore enlarged in diameter and threaded as indicated at 15 for receiving the threaded end 16 of a detachable nozzle 17.

The outer end of connector 14 is internally threaded to receive a suitable hose connection 18 which leads from a source of compressed air and abradant material (not shown). The ma-

terial used is preferably fine shot but sand may be used, if desired.

The inner end of connector 14 is tapered outwardly, as indicated at 19, so that when said connector is attached to the holder a suitable clearance is provided between the shouldered portion 20 of the holder and said tapered end so as to receive any abradant material therebetween and insure at all times a close fit adjacent to the peripheral surfaces of said parts. The bore of said connector 14 is provided with a circular shoulder 21 against which the end of extension 12 is brought when the connector is screwed on to said holder. Thus a bore chamber uniform in diameter is provided between the connector and the holder and the end of extension 12 is protected by said shoulder against the abrasive action of the material traveling through said bores.

The enlarged threaded bore 15 of the forward end of the holder is provided with a shoulder 22 against which the inner or threaded end of the nozzle is located when the latter is screwed in position on the holder. Thus a smooth bore connection is provided between the holder and the nozzle and the inner end of the latter is protected against wear by the action of the abradant material.

The bore of the nozzle is tapered outwardly, as indicated at 24. A suitable distance from the mouth or discharge end 25 of the nozzle (in the present case for a distance of about one-eighth of an inch) the bore is formed straight, as indicated at 26, and is 0.075 inches in diameter which is also the size of the discharge mouth or end 25.

Thus it will be observed that the nozzle has a comparatively outwardly tapered bore which terminates in a short section of straight bore and of small diameter. This causes a larger amount of shot or abradant material to be discharged from the nozzle for a given period of time. The short section of straight bore of uniform diameter with the discharge mouth or opening protects the latter against undue wear and insures the discharge of the abradant material in a stream capable of being used for feather edge work on stone.

In a nozzle having a tapered bore throughout its entire length the stream of material immediately upon issuing from the nozzle spreads out or diverges outwardly, whereas in my improved nozzle, due to the short terminal portion 26 being formed straight, the material issues from the nozzle in a fine stream, which for a short distance from the nozzle continues in a straight line, thereby enabling the use of the nozzle for fine or feather edge work in close proximity to the stone.

The holder is provided with knurled peripheral

portions 27 and 28 to permit a better and more convenient finger grip in working upon a stone.

The nozzle 17 is preferably provided with a pair of oppositely disposed flat faces 29 which 5 permit the nozzle to be tightened in position by the use of a suitable tool, such as a wrench. The outer end of connector 10 receives the threaded end of a nipple 30, the latter having secured thereto in any suitable manner a flexible 10 hose connection 21 by means of which the abrasant material is supplied to the tool.

Preferably the nozzle 17 is case hardened so as to make it wear-resistant and prolong the life thereof. The particular construction of the nozzle, including the tapered bore 24 and the straight discharge portion 26, the diameter of which latter is not more than 0.075, causes the shot to be discharged from said nozzle in such a manner that fine designs can be worked upon the stone. 15 This kind of work cannot be performed with the nozzles now in use. The holder is so arranged that it can be conveniently held in the hand without tearing the fingers. As both the nozzle and the connector are detachable they can be 20 replaced when worn out at small cost, thereby eliminating the necessity of discarding the whole tool.

I claim:

1. In a device of the class described, the combination of a tubular holder adapted to be held by the operator's fingers similarly to a pencil, said holder having a tapered forward end and a bore of uniform diameter throughout its length and terminating in the forward end in an enlarged bore internally screw-threaded, said 35 holder having a reduced rear end provided with

an external screw thread, a nozzle having an extension formed with an external screw-thread for detachably engaging the internally threaded bore of the forward end of said holder, said nozzle having a tapering bore, the larger end of which is of the same diameter as the bore in said holder and the outer end of which terminates in a short bore of comparatively small and uniform diameter, a connector having one end internally screw-threaded for detachably engaging the reduced rear end of said holder, and a flexible hose connected to said connector. 80

2. In a device of the class described, the combination of a tubular holder shaped to be held between the operator's fingers in the same manner as a pencil, said holder having a tapered forward end and a peripherally disposed concave portion under said forward end bounded on each side by knurled portions to provide a firm finger grip, the rear end of said holder being provided with an internally threaded extension and the forward end being tapered and having an enlarged bore internally screw-threaded, a discharge nozzle having one end externally screw-threaded for detachably engaging the threaded bore of said holder, said nozzle having a forwardly tapering bore, the inner end of which is of the same diameter as the bore of said holder and the outer end of which terminates in a straight short bore not more than 0.075 inches in 195 diameter, a connector having an internally screw-threaded end for detachably engaging the externally screw-threaded end of said holder, and a flexible hose detachably connected to the other end of said connector. 113
